E. E. DOUGHERTY

COIN OPERATED LOCK

Original Filed Aug. 7, 1922

FIG. I.

FIG. 3. 38

FIG. 2.

INVENTOR

Edwin E. Dougherty,
Josheley
Attorney.

UNITED STATES PATENT OFFICE.

EDWIN E. DOUGHERTY, OF LOS ANGELES, CALIFORNIA.

COIN-OPERATED LOCK.

Application filed August 7, 1922, Serial No. 580,142. Renewed July 13, 1925.

To all whom it may concern:

Be it known that I, EDWIN E. DOUGHERTY, a citizen of the United States, and a resident of Los Angeles, in the county of Los Angeles and State of California, have invented new and useful Improvements in Coin-Operated Locks, of which the following is a specification.

This invention relates to coin controlled locks, particularly that type of lock used for preventing access to compartments, lavatories and the like unless a coin is placed within the lock. My invention has for its main object the provision of a lock of the above character that is of simple construction and readily accessible for repair, adjustment and removal of coins.

It will be understood in the consideration of the invention that in usual types of coin controlled locks the mechanism is subject to inspection and repair only by removing the lock from the door to which it is attached. It is therefore another object of the invention to provide a lock of the above type including means whereby a person possessing the proper key may quickly gain access to the mechanism without removing the lock from the door.

Another object of the invention is the provision of means whereby the mechanism may be assembled completely on a single plate like part of the lock casing so that by removal of a part of the casing the operation of the complete mechanism may be observed, and articles which may clog the device be readily removed; it being understood that metal slugs, cardboard discs and the like are sometimes placed in the coin slot in substitution for a coin.

My invention contemplates the use of a knob on each side of the lock so that while a door can be opened from the outside only when a coin is employed, it may be opened from the inside without the use of a coin, and it is therefore another object of the invention to provide a lock in which the coin will serve directly as part of the mechanism and remain in operative position until the door is opened from the inside; whereupon the coin will fall out of operative position.

Other objects and advantages will appear hereinafter.

I have illustrated by the accompanying drawings a preferred form of the invention.

In the said drawings,

Figure 1, is a view in perspective of the said form of the invention, a front portion of the housing being shown removed to reveal the mechanism.

Figure 2, is a view in section seen on a line 2—2 of Fig. 1.

Figure 3, is a view in section seen on a line 3—3 of Fig. 2.

More specifically, reference being had to the said figures and the numerals indicating respective parts; 5 indicates a back wall of a housing 6, the complete housing consisting of a box like member 7, and the aforesaid back wall 5 which may be secured to a door, such as 8, on the outer side thereof.

The lock is provided with the usual sliding bolt 9, having a bolt end 10 which is guided and held in position relative to wall 5 by a bearing 11. Said bolt is arranged to remain in sliding contact at all times with the inner surface of wall 5, and in addition to bearing 11, said bolt is further held by an adjusting screw 12. Said screw is threaded into a boss 13 formed integral with the bolt, and it will be apparent that the screw may be adjusted so that it abuts the inner surface 14 of member 7 to hold the bolt against lateral movement.

The lock includes two door knobs 15 and 16, respectively, for operating the bolt from respective sides of the door. The knob 15, known as the outside knob, is formed with a square bore 16', and knob 16, known as the inside knob, is similarly formed. It is intended that the inside knob be capable at all times of retracting the bolt without the aid of a coin. For this purpose an arm

17 is provided which is formed integral with a shaft 18, and which is formed with a square end extending into the bore of said knob. Said arm abuts boss 13 so that a partial revolution of the inside knob will retract the bolt. Shaft 18 extends through a boss 20, which boss serves to hold a coil spring 21. An end 23 of said spring abuts boss 13 to hold the bolt yieldably in advanced position, and the other end 23 of said spring is held by a screw 24. The inside knob is threaded as at 25, and the shaft to which it is secured is also threaded. The knob screws onto the threaded shaft, and to hold it against being accidentally unscrewed, a jam nut 27 is provided which is also screw threaded onto the shaft. While

spring 21 serves to yieldably hold the bolt in advanced position, the movement thereof is limited by an end 28 of boss 13, which end extends through a slot 29 formed in wall 5. A stop 30 is formed on the bolt to limit the forward movement of arm 17 so that it cannot be moved forwardly far enough to interfere with other moving parts of the lock. While the door may be opened from the interior of a compartment without the use of a coin, an authorized person possessing a key (not shown) may open the door from the outside. Arm 17 is formed with a lug 31, aligning with an opening (not shown) in the front of the housing, through which a key may be inserted to engage said lug and move said arm sufficiently to bring the bolt to retracted position.

Shaft 18' bears in a boss 32, around which is wound a spring 33. Integral with said shaft an arm 34 is formed, and spring 33 is bent to engage said arm as at 33' to hold said arm yieldably in the normal position shown in Fig. 1. Said spring is secured at the outer end as at 35 to a screw 36. Shaft 18' passes outwardly through an opening in the front part of the housing so that the knob may be secured thereto. It will be seen that by turning the outside knob, arm 34 will be moved toward arm 17, but is in no way connected to the bolt, and therefore turning of the outside knob will not move said bolt, unless a coin 37 is inserted in a coin slot 38 so that it falls into operative position as shown in Fig. 1. The shaft is provided with a square end which is inserted in the square bore 16' of knob 15, whereby said knob and said shaft will turn together.

Access may be gained to the coin space through an opening 52 in the front of the lock. Said opening is closed by a closure plate 53 which is formed with a lug 53' to assist in holding it in place, and a common lock 54, secured on the inside of said plate closure, co-operates with the lug to prevent the closure being removed except upon removal of the closure.

The coin slot is formed by a three sided member 56 abutting and secured to wall 5. The bolt is formed with a recess 57 of greater length than the diameter of the coin to be used and of slightly greater depth than the thickness of said coin. Said recess, together with the adjacent part of the wall, serves to enclose a rectangular space 58 through which a coin may slide. If not obstructed the coin to be used in opening the door will slide through said space and fall into the coin space.

In order that a coin may not fall through said space when inserted in the coin space, and for the purpose of causing the coin to act as part of the mechanism, an obstruction is provided in the form of two spaced fingers

59 and 60, each properly positioned above and below the bolt respectively, and practically abutting wall 5. Said fingers are movable with arm 34, and therefore are preferably formed integral therewith. The lower finger virtually acts as a rest on which the coin lies, while the upper finger acts as a connection between the arm and the bolt.

The operation of the lock is as follows: Turning of the outside knob will not retract the bolt, inasmuch as no physical connection exists therebetween. A coin inserted in the coin slot will fall into the recess provided in the bolt, and the fingers will co-act with the margins of said recess to hold the coin in the position shown. Now, upon turning the outside knob the bolt will be retracted. When the outside knob is released the bolt returns to normal position and the fingers still act to retain the coin in position. This is due to the fact that spring 23 compels arm 7 to hold the same relative position with regard to the bolt, and thus the coin is still held in place. When a person, having gained access to a compartment by opening the door with the aid of a coin, forces the door closed the bolt will of course be forced inwardly in a manner common to bolts of this character. While the bolt is being retracted arm 34, with its fingers will remain inert. Thus the effective length of the recess in the bolt is increased, and the coin is free to fall into the coin space.

In installing the lock on a door, the plate 5 is secured thereto, and thus it will be seen that the member 7 of the housing may be removed without removing the lock from the door. If it is desired to gain access to the mechanism of the lock, the outside knob is removed. Then the hand-hole plate is removed so that the screw 50 may be reached and removed. It will be apparent that any one, not possessing the proper keys, cannot gain access to the coin space of mechanism of the lock, while authorized persons possessing the proper keys may quickly inspect the mechanism or remove articles, such as paper or slugs that may have clogged the mechanism. To remove the coins from the coin space, it is only necessary to remove the hand-hole plate with the aid of the proper key.

In assembling or adjusting the lock, the adjustment screw is moved outward until the head abuts the inner surface of member 7 of the housing. Thus the bolt is accurately guided and held in its proper position to facilitate smooth and accurate movement of said bolt.

It will be seen now that I have provided a coin controlled lock comprising the very minimum of parts and readily installed, repaired and adjusted, and while I have shown and described a specific construction and arrangement of parts, I do not limit myself

thereto, but may employ other constructions and arrangement of parts as occasion requires, without departing from the spirit or enlarging the scope of my invention, 5 within the appended claims.

I claim:

1. In a device of the character described, a coin chute provided with a discharge aperture having opposed side margins spaced 10 apart a distance greater than the diameter of a coin, a retractile bolt below said coin chute provided with a slot through which the coin may fall substantially without interference; the slot having a rear end margin, 15 means for limiting the forward movement of said bolt, yieldable means holding said bolt in forward position as limited by said stop; a finger normally disposed at right angle to the bolt and extended under 20 the slot forwardly of the vertical median line of said discharge aperture, another fin-

ger paralleling said first named finger extended above the bolt and slot disposed forwardly of the first named finger, said rear end margin and said fingers forming a support for a coin and arranged to coact when the bolt is in advanced position, to intercept and support a coin gravitating from said chute, an outside knob, and means whereby said knob on being turned moves 25 both fingers simultaneously rearward in the general direction of the retrograde movement of the lock to retract the bolt through the agency of a supported coin.

2. A lock as in claim 1, and further including, yieldable means tending to hold said fingers in normal position as described, an inside knob, means effective upon turning said inside knob for retracting said bolt without effecting movement of said fingers. 35

EDWIN E. DOUGHERTY.
